DESIGN FOR A REVERSIBLE DENTAL RETRACTOR

Herman Richard Nerbas, Roseburg, Oreg.

Application September 14, 1940, Serial No. 95,049

Term of patent 7 years

To all whom it may concern:

Be it known that I, Herman Richard Nerbas, a citizen of the United States, residing at Roseburg, in the county of Douglas and State of Oregon, have invented a new, original, and ornamental Design for a Reversible Dental Retractor, of which the following is a specification, reference being had to the accompanying drawing, forming part thereof.

Figure 1 is a side elevational view of a re-

versible dental retractor showing my new design.

Figure 2 is a plan view thereof, and

Figure 3 is a plan view of the reversible dental retractor shown in a position reverse to that illustrated in Figure 2.

I claim:

The ornamental design for a reversible dental retractor, as shown.

H. RICHARD NERBAS.
